PHOTOCELL CONSTRUCTION

Charles Ekstein, Brooklyn, N. Y., assignor to Vitro Corporation of America, New York, N. Y., a corporation of Delaware

Application March 21, 1952, Serial No. 277,807

9 Claims. (Cl. 136—89)

1

My invention relates to cell constructions for devices electrically responsive to radiation.

It is an object of the invention to provide an improved construction and method of construction for devices of the character indicated.

It is another object to provide a more rugged cell construction which may be less electrically sensitive to mechanical shock.

It is a further object to provide a cell construction inherently possessing greater energy-gathering properties than are inherent in the basic radiation-responsive element of the cell.

Other objects and various further features of novelty and invention will be pointed out or will become apparent to those skilled in the art from a reading of the following specification in conjunction with the accompanying drawings. In said drawings, which show, for illustrative purposes only, preferred forms of the invention:

Fig. 1 is an enlarged view in perspective of a cell construction incorporating features of the invention;

Fig. 2 is a vertical sectional view to illustrate a step in the construction of the assembly of Fig. 1;

Fig. 3 is an enlarged side view of the radiation-responsive element of Fig. 1 and of electrical connections thereto;

Fig. 4 is a view similar to Fig. 3 but illustrating a modification; and

Fig. 5 is a view similar to Fig. 2 and illustrating an alternative method of construction.

Briefly stated, my invention contemplates an improved construction and method of construction for radiation-responsive cells. The construction may utilize the most brittle of sensitive crystalline materials and yet be rendered relatively insensitive to mechanical shock. This is achieved by securing spaced electric-contact portions of the crystal to enlarged flat-headed ends of electric-terminal members over the flat areas thereof, and by casting the assembly in a body of plastic material transparent to the radiation. The energy-gathering properties of the complete assembly may be greatly enhanced by so contouring a substantial external area of the body as to form a lens, to produce a ray bundle convergent upon the sensitive part of the crystal or the like. Various further features will be described for the promotion of improved electric connections and for the enhanced resistivity to mechanical shock.

In Figs. 1 to 3 of the drawings, my invention is shown in application to a single-element cell, which may employ a radiation-responsive ele-

2

ment in the form of a single crystal 10. The crystal 10 may be of cadmium sulphide or zinc sulphide, or of the selenides of such metals. The crystal 10 may thus comprise an elongated prismatic element having parallel opposed faces 11—12 with electric-contact portions 13—14 at spaced locations thereon. In the form shown, the contact portions 13—14 are at the ends of the crystal 10, and their extent determines or limits the sensitive area between these ends.

In accordance with a feature of the invention, electrical contact to the contact areas 13—14 is made by a plurality of relatively rigid terminal members 15—16 having enlarged heads 17—18 for large-area contact with and support of the contact portions 13—14 of the crystal 10. The terminal members 15—16 may be locally weakened, as at 22, for a purpose to be made clear. During assembly the heads 17—18 may be temporarily secured to the contact portions 13—14 on the underface 12 of the crystal, as by means of a suitable adhesive; thereafter, a coating of electrically conducting material may be applied to overlap parts of the terminal members 15—16 and of the electric-contact portions 13—14. The coating 19 may be of a commercially available material, such as Aquadag, and I prefer that the coating shall entirely overlap all parts of the crystal except the intermediate portion which is to remain radiation-responsive. The coating 19 also preferably overlaps the entire exposed portion of the heads 17—18.

In the alternative construction of Fig. 4, a permanent electrically conducting relation is further promoted by employment of flexible wires 20 coiled and preferably welded at 21 to the terminal members 15—16 (preferably between the heads 17—18 and weakened portions 22) and cemented at the other ends to other parts of the electric-contact portions 13—14. The conductive coating may then additionally overlap part of the wires 20, as indicated at 19'.

In assembling the device, clamping means 23 may first hold the terminal members in desired spatial relation, with the faces of heads 17—18 aligned in the same plane. Adhesive may then be applied to these faces or to the electric-contact parts of element 10, after which the element 10 is pressed against the heads 17—18 and the adhesive allowed to set. Electrical contact is then enhanced by applying the conductive coatings 19, with or without wires 20, as dictated by specific application requirements. The clamped assembly may then be inverted over an open die or mold 24, which may be contoured to the de-

sired final cell shape. In the form shown in Fig. 2, this shape is generally cylindrical, with a lens-forming contour at the end 25; the plastic forming the cell body may be of a transparent insulating material known to the trade as Kelon, which may be simply poured into the mold, to a depth to cover the weakened portions 22.

In setting the clamp 23 on members 15-16, and in elevating clamp 23 on the rim of the die 24, care should be taken to position the radiation-sensitive area 11 of element 10 so as to assure interception of converging rays from the lens shape 26. I prefer that the area 11 shall be symmetrical about the optic axis of lens 26 and substantially at the focus thereof.

Fig. 5 illustrates an alternative method of casting for cells to be finished with a flat end face adjacent the sensitive area of element 10. The terminal members may be frictionally held in rubber-like bushings 21, fitted in holes 28 in a base plate 29, so that the assembly 10-15-16 (including weakened portions 22) may project upwardly into the bore 30 of a top die plate 31; alternatively, the bushings 21 may be replaced with soap or like packing to provide the desired temporary frictional support. In casting, the insulating transparent plastic may fill the bore 30 to excess, so that after the plastic has set the top face may be ground and polished flat, as at the section suggested by the dotted line 32. The completed cell may be removed by parting the die plates 29-31 to expose the cell body, and by then grasping the cell body to remove the terminal members 15-16 from the lower plate 29.

It will be seen that I have disclosed an improved cell construction and method of construction, featuring mechanical ruggedness and enhanced energy-gathering properties. My construction lends itself to quantity production, as by employing elongated clamps 23 to support terminal members for a plurality of cells, or by providing multiple molds in the same die plate. The weakened portions 18, cast within the cell body, serve to anchor the terminal members 15-16 and to prevent twisting of the lead wires within the plastic, thus preserving electrical continuity.

While I have described the invention for the preferred forms shown, it will be understood that modifications may be made within the scope of the invention as defined in the claims which follow.

I claim:

1. In a cell construction of the character indicated, an elongated crystalline element electrically responsive to radiation, electric-contact portions at longitudinally spaced locations on one surface of said element, relatively rigid terminal members each including an enlarged supporting head at one end thereof, said heads being rigidly secured to said element at different of said electric-contact portions and in electrically conducting relation therewith, and a body of plastic material transparent to radiation and completely encasing said element and parts of said terminal members near said ends thereof, each said terminal member including a locally weakened mechanical-shock-resistant portion spaced from said contact portions and encased by said plastic material.

2. In a cell construction of the character indicated, an elongated prismatic crystal electric-

cally responsive to radiation and including terminal portions at opposite ends thereof, means shielding said ends against electrical response to radiation, whereby the portion intermediate said ends may be thus responsive, two terminal members each including a flattened relatively large area head at one end thereof, said heads being secured to the terminal portions of said crystal in electrically conducting relation therewith, and a body of plastic insulating material transparent to radiation and completely encasing said element and parts of said terminal members near said ends thereof, each said terminal member including a locally weakened portion spaced from said crystal and contained within said body.

3. A construction according to claim 2, in which said enlarged supporting heads are formed integrally with said terminal members.

4. A construction according to claim 2, in which said terminal members are of relatively rigid wire with said heads being formed as flattened upset ends thereof.

5. A construction according to claim 2, in which a conductive coating overlaps parts of said heads and of said crystal ends.

6. A construction according to claim 2, in which a relatively flexible conducting member is secured to one of said terminal members and to the corresponding crystal end independently of the terminal-head connection to said end.

7. A construction according to claim 6, in which a conductive coating overlaps parts of said flexible member and of said crystal end and of said one terminal member.

8. In a cell construction of the character indicated, a cell body including a convex outer surface in an insulating material transparent to radiation, a radiation-responsive element including a sensitive area intimately bonded to said material within said body and facing said surface, and electrical leads to said element on opposite sides of said area, said leads including locally weakened portions spaced from said element and fully contained within and intimately supported by said body.

9. In an electrical cell of the character indicated, an elongated prismatic crystal electrically responsive to radiation, two relatively rigid elongated lead members rigidly secured to spaced parts of said crystal, said lead members including locally reduced and thus weakened portions intermediate said crystal and the remote ends of said lead members, and a single radiation-transparent body intimately encasing said crystal and said lead members at least to said weakened portions, with the remote ends of said lead members projecting externally of said body.

CHARLES EKSTEIN.
